US00D819032S

(12) **United States Design Patent** (10) Patent No.: **US D819,032 S**
(45) Date of Patent: **** May 29, 2018**

(54) **DATA PROCESSING APPARATUS**

(71) Applicant: **BELDEVIM**, Luxembourg (LU)

(72) Inventors: **Bernard Blanchet**, Versailles (FR);
Edouard De Ledinghen, Tessel (FR);
Lionel Laurent, Montfort L'Amaury (FR)

(73) Assignee: **BELDEVIM**, Luxembourg (LU)

(**) Term: **15 Years**

(21) Appl. No.: **35/502,195**

(22) Filed: **Jun. 30, 2016**

(80) **Hague Agreement Data**

Int. Filing Date: **Jun. 30, 2016**

Int. Reg. No.: **DM/092898**

Int. Reg. Date: **Jun. 30, 2016**

Int. Reg. Pub. Date: **Dec. 30, 2016**

(51) **LOC (11) Cl. 14-02**

(52) **U.S. Cl.**

USPC **D14/383**

(58) **Field of Classification Search**
